UNITED STATES PATENT OFFICE.

FRANK L. McCORMICK, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

AUTOMATIC ROLL-CHANGER FOR MUSICAL INSTRUMENTS.

1,110,001.

Specification of Letters Patent.

Patented Sept. 8, 1914.

Application filed September 21, 1912. Serial No. 721,586.

To all whom it may concern:

Be it known that I, FRANK L. McCORMICK, a citizen of the United States, residing at North Tonawanda, in the county of 5 Niagara and State of New York, have invented new and useful Improvements in Automatic Roll-Changers for Musical Instruments, of which the following is a specification.

10 This invention relates to the music roll magazines or carriers used in connection with automatic musical instruments and adapted to carry a series of music rolls, to enable the instrument to play a comparatively large 15 number of selections without changing the rolls by hand, as is the case in ordinary instruments controlled by such sheets.

The present invention relates more particularly to improvements in the automatic 20 roll changer or carrier shown and described in Letters Patent of the United States No. 769,671, granted September 6, 1904, to W. R. Verstraelen and C. Alter. The device of this 25 patent comprises essentially a rotary horizontal carrier adapted to contain a plurality of music rolls, a single take-up roll common to the several music rolls, transfer or carrying arms for delivering the free end of each 30 music sheet to the take-up roll, driving mechanism for unwinding and rewinding the music sheets and mechanism for advancing the carrier a step after playing and rewinding each roll to bring another roll into 35 playing position. In the patent above referred to, these movements are produced largely by pneumatic means.

One of the objects of my invention is the production of a roll-changer of this character in which the various movements are produced principally by mechanical means, with a view of rendering the apparatus more reliable in action.

A further object is to simplify the construction of such devices and reduce their 45 cost.

In the accompanying drawings consisting of 6 sheets: Figure 1 is a front elevation of the device. Fig. 2 is a sectional end view thereof, on an enlarged scale, the plane of 50 the sectional portion being on line 2-2, Fig. 1. Fig. 3 is a side elevation of parts of the actuating mechanism of the roll-carrier, showing the same in a different position from that illustrated in Fig. 2. Figs. 4 and

5 are transverse sections on lines 4-5, Fig. 55 1, showing the parts in different positions. Fig. 6 is a transverse section on line 6-6, Fig. 1, showing the roll driving mechanism. Fig. 7 is an end elevation of the apparatus viewed from the end at which the main driving mechanism is located. Figs. 8, 9 and 10 are perspective views, showing different positions of the roll-driving mechanism and its locking means. Fig. 11 is a perspective view of the flushing valve and coöperating parts. Fig. 12 is an elevation of the inner side of the actuating wheel of the roll carrier and adjacent parts. Fig. 13 is a fragmentary transverse section of the apparatus showing the position of the transfer arms preparatory to being elevated by the rod of the music sheet.

Similar characters of reference indicate corresponding parts throughout the several views.

The stationary main frame of the apparatus may be of any suitable construction, that shown in the drawings comprising a pair of upright end-pieces or plates 1 connected near their upper and lower portions 75 by horizontal tie rods 2.

Mounted horizontally in the upper portion of this frame is the rotary roll carrier or magazine which in the preferred construction shown consists of a horizontal 85 shaft 3 journaled in suitable bearings in the end-pieces 1 and carrying a pair of spaced heads 4 fixed thereon and between which the music rolls 5 are supported in a circular series. One of these heads, preferably the 90 left hand one, carries the usual yieldable bearing studs 6 which receive the adjacent journals of the music rolls, while the other head carries the customary rotary sockets 7 which receive the usual winged journals of 95 the rolls. In the construction shown in the drawings, each of these sockets is carried by a short shaft 8 journaled in said head and provided at its outer end with a clutch member 9 and preferably also a grooved pulley 100 10 embraced by a flexible brake band 11 for checking rotation of the music roll to insure proper unwinding and winding of the music sheet.

At one end of its shaft the roll carrier 105 is provided with a hand wheel 12 by which it may be manually set to play any desired music roll. For this purpose the shaft is

provided adjacent to the hand wheel with a pointer 13 which traverses a fixed dial 14 bearing numbers or other suitable indications corresponding to indications 15 on the roll carrier.

The roll carrier is intermittently and automatically rotated preferably by the following mechanism: 16 indicates the main or power shaft which is constantly rotated during the operation of the instrument, by an electric or other suitable motor, not shown in the drawings, this motor being started in practice by depositing a coin in a suitable coin-controlled device applied to the instrument, in a well known manner. Arranged parallel with this driving shaft is a shaft 17 driven therefrom by a horizontal shaft 18 and bevel gears 19, 20, 21 and 21¹, as shown in Fig. 1. The shaft 17 is journaled at its upper and lower ends in brackets 22, 23 projecting from the adjacent end-piece 1, and has splined thereon a friction wheel 24 which engages an upright friction disk 25 secured to a shaft 26 journaled in a bearing 27 mounted on said end-piece. Carried by the latter and arranged below said friction disk is a longitudinal arbor 27 upon which is rotatably mounted a sprocket wheel 28 driven by a chain 29 from a sprocket wheel 30 on the hub of said disk. Secured to the hub of the lower sprocket wheel 28 is a spur pinion 31 which meshes with a spur wheel 32 secured to the adjacent end of a longitudinal shaft 33 journaled in the lower portion of the end-pieces 1, by which construction the last-named shaft is constantly driven from the main shaft. To enable the speed of the driven parts to be changed or adjusted as required, the friction wheel 24 is movable toward and from the axis of the friction disk 25. For this purpose the hub of the friction wheel is annularly grooved to receive the pins of a vertically-swinging fork 34 fixed to a rock shaft 35 carried by the bracket 22. This rock shaft has an arm 36 which is engaged by the lower end of an adjusting screw 37 threaded in the bracket 22. Upon turning this screw in one or the other direction, the friction wheel is moved toward or from the axis of the friction disk, correspondingly increasing or diminishing the speed of the latter and the parts connected therewith.

Fixed upon the left hand end of the roll-carrier shaft is a wheel 38 provided with radial slots 39 extending inwardly from its edge and corresponding in number and position to the bearing studs 6 and sockets 7 of the roll carrier. These slots are successively engaged by a pin 40 carried by an actuating wheel 41 having sprocket teeth and mounted on a stud projecting from the adjacent end-piece 1, said pin entering and leaving one of said slots during each complete rotation of said sprocket wheel and

thereby turning the roll carrier forward one step or the distance from one music roll to the next. Said sprocket wheel is intermittently driven from the constantly rotating shaft 33 by a chain 42 passing around the same 70 and around a sprocket pinion 43 loosely sleeved on said shaft. The pinion 43 has clutch pins or members 44 adapted to be engaged by a coöperating clutch member 45 splined upon the shaft 33 and connected with the forked lower end of a clutch-lever or bell crank 46, as shown in Figs. 1 and 2. This clutch lever is pivoted to a bracket 47 projecting from the adjacent end-piece 1 and its lower arm is constantly drawn by a spring 48 in the proper direction to engage said clutch members. The clutch lever is swung in the opposite direction to disengage said clutch-members by means of a thrust bar or link 49 bearing with its forked or slotted lower end against the upper arm of said lever and pivoted at its upper end to the lower arm of a controlling lever 50 pivoted to the adjacent end-piece 1. The upper arm of this lever is provided with a nose 51 which normally rides upon an annular flange 52 of the sprocket or actuating wheel 41 and which is adapted to enter a notch 53 in said flange once during every rotation of said wheel. The upper end of the lever 50 is pressed 95 against said notched flange by a suitable spring 54, preferably a leaf spring secured to the face thereof and acted on by a cam or projection 55 secured to a longitudinal rock shaft 56 journaled in the end pieces 1 100 underneath the roll carrier. A spring 57 which connects the upper arm of the lever 50 with the adjacent end piece 1 tends to withdraw the nose of said lever from the notch 53 of the sprocket-wheel flange 52. 105 When the shaft 56 is rocked downwardly, the cam 55 tensions the leaf-spring 54 which thereby overcomes the resistance of the spring 57 and presses the upper end of the lever 50 against said sprocket-wheel flange. 110 When during the rotation of said sprocket wheel said notch comes into register with the nose of the lever 50, the nose enters the notch, under the pressure of the spring 54, swinging the lower arm of said lever downward and causing the thrust bar 49 to rock the clutch lever 46 in the proper direction to disengage the clutch members 44, 45 and stop the rotation of the sprocket wheel 41 and the roll carrier. When the shaft 56 is 115 rocked backwardly, the cam 55 is withdrawn from said leaf-spring, relaxing the latter and allowing the other spring 57 to withdraw the controlling lever 50 from the notch of the sprocket wheel 41, as shown in Fig. 120 2. By this action the slotted lower end of the thrust bar is drawn upwardly away from the upper arm of the clutch lever 46, releasing the latter and allowing its spring 48 to swing its lower arm inwardly, thereby 125 130

again throwing the clutch members into engagement, preparatory to turning the roll-carrier another step.

After each forward step or partial rotation, the roll carrier is positively held from turning by a retaining lever 58 preferably pivoted to the inner side of the left-hand end-piece 1 and carrying at its upper end an anti-friction roller 59 which interlocks successively with the equidistant notches 60 of a wheel 61 fixed to the shaft of the carrier, there being such a notch in line with each music roll in the carrier. The upper arm of said retaining lever is constantly urged toward said locking wheel by a spring 62. The notches 60 of said wheel are preferably V-shaped or of cam-form, as shown, so that as the roller of the lever moves into the notches it partially turns the roll carrier until the roller becomes fully seated in the notch when it arrests the rotation of the carrier. The lever 58 is positively locked in position to prevent rotation of the roll carrier by a vertically-swinging lock or latch 63 mounted on a pivot 64 carried by the adjacent end-piece 1 and adapted to be swung upward in front of the lower arm of said lever, (as shown in Fig. 5) by a spring 65 connected with the latch. The upward movement of this latch is limited by a stop pin 65^a projecting inwardly from said end-piece.

66 indicates the take-up roller arranged horizontally underneath the front portion 35 of the roll carrier and 67 is the tracker board arranged between the take-up roll and the roll carrier and over which the sheet of the active music roll travels when the take-up roller is driven in the proper direction to unwind the sheet from said roll. For this purpose each music roll is provided at its free end with a transverse rod 68 projecting beyond the edges thereof and adapted to be engaged by hooks 69 carried by the end flanges of the take-up roll, substantially as shown and described in the Letters Patent hereinbefore referred to. In the normal wound-up condition of the music rolls these rods are yieldingly confined in radial notches 70 in the heads of the roll-carrier by suitable spring catches 71 which prevent accidental escape of the rods from the notches.

As in the aforesaid Letters Patent, the 55 end rod 68 of the music roll to be played is carried or transferred from the notches in the roll-carrier heads to the hooks of the take-up roll by a pair of vertically-swinging arms 72 arranged on the outer sides of said heads and secured to the rock shaft 56. These transfer arms are provided on their undersides near their free ends with seats or notches 73 which receive the rods of the music rolls and with beveled noses 74 which 60 engage behind the rods and direct them into

said notches when the roll carrier is turned forward a step to bring a music roll into playing position. These arms are yieldingly held in their elevated position by a lever 75 pivoted to the inner side of one of the end pieces 1, preferably the left-hand one, and carrying at its upper end an anti-friction roller 76 which bears against the face of a cam 77 secured to the rock shaft 56. This lever is constantly pressed against said cam by a spring 78 connecting its lower arm with the stationary part of the main frame. The downward movement of the transfer arms 72 is effected by a trip pin or stud 79 carried by the sprocket wheel 41 and arranged to engage an arm 80 fixed to the rock shaft 56, once during each rotation of said sprocket wheel, the downward movement of this rock arm being limited by a suitable stop 81, as shown in Fig. 3.

A pin 82 which takes part in the upward movement of the transfer arms and which is preferably carried by the hub of the cam 77 is arranged to engage the tail of the latch 63 during the final upward movement of said arms, so as to swing the long front arm of the latch downward and withdraw it from the retaining lever 58, as shown in Fig. 4, thereby releasing said lever and permitting the roll carrier to turn. When the transfer arms are lowered, the pin 82 recedes from the tail of said latch, allowing the latter to be swung upward to its locking position by its spring 65, as shown in Fig. 5.

The take-up roll and the music rolls may be driven by any suitable unwinding and rewinding mechanism, but I prefer to use the mechanism shown in the drawings which is constructed as follows: 83 indicates a spur gear secured to the shaft of the take-up roll and adapted to be engaged by a laterally-sliding pinion 84 splined upon the shaft 26 which carries the friction disk 25, so that when said pinion is shifted into engagement with said spur gear the take-up roll is driven in the proper direction to unwind the music sheet from the active music roll.

85 is a horizontal rewinding shaft arranged parallel with the friction-disk shaft 26 and located endwise opposite the circular path in which the clutch members of the music rolls travel by the rotation of the roll-carrier. Upon this rewinding shaft is splined a clutch member 86 with which the corresponding clutch members of the music rolls are adapted to be engaged successively for rewinding the music sheet thereon. Said rewinding shaft is driven from the shaft 26 by gear wheels 87, 88 mounted on said shafts, and an intermediate idler 89 whereby the rewinding shaft is rotated in the opposite direction to the take-up roll. The splined clutch member and splined pinion 84 are

connected with opposite arms of a shifting frame 90 pivoted between its ends to brackets 91 extending inwardly from the adjacent end-piece 1. The pivot of said frame is arranged at right angles to the axis of the roll carrier so that the frame rocks lengthwise of the latter. A spring 92 connecting the upper end of this shifting frame with a bracket 93, tends to rock the frame into the position in which the pinion 84 engages the gear wheel 83 of the take-up roll and the clutch member of the rewinding shaft clears the opposing clutch member of the roll carrier. The frame is rocked in the opposite direction for throwing the take-up roll out of gear and the active music roll into gear with the driving mechanism by means of a sliding shipper bar 94 guided horizontally in the right-hand end-piece 1 and connected at its inner end with a stud 95 projecting laterally from the lower arm of said frame. For the purpose hereinafter described, a yieldable connection is preferably employed between said frame and the shipper bar. The connection shown in the drawings, Figs. 8, 9 and 10, consists of a spring 96 connecting a pin 97 of the shipper bar with a rigid arm 98 on the frame, the inner end of the shipper bar having a fork or longitudinal slot 99 which permits it to move lengthwise on the stud of said frame. Ordinarily this connection is practically rigid, the spring 96 being made stiff enough for that purpose, but in case the clutch member of the rewinding shaft 85 should not engage properly with an opposing clutch member of the roll-carrier, said spring will yield and prevent breakage of any parts.

The shipper bar is designed to be actuated immediately after a roll has been played, so as to rewind the sheet upon the spool of the played roll. Any suitable means may be employed for this purpose, but I prefer to employ mechanism including a pneumatic controlled by a perforation in the music sheet. In the preferred mechanism shown in the drawings, 100 indicates a vertically swinging lever pivoted at 101 to a block 102, and 103 indicates a rod connecting the angular portion of said lever with an upright lever 104. The latter is pivoted at its lower end to a bracket 105, and at its upper end to the shipper bar, whereby when the long arm of the lever 100 is depressed, the shipper bar is pulled outwardly, throwing the take-up roll out of gear and the active music roll into gear with the driving mechanism. Pivoted to said long arm is a trip or thrust-bar 106, the upper end of which is laterally movable into and out of the path of a rotary cam 107 fixed to the power shaft 16. A spring 108 which connects the thrust-bar with the lever 100 tends to draw the bar out of range of the cam 107, while a pneumatic 109, when col-

lapsed, swings the upper end of the bar under the face of said cam, so as to be depressed thereby. For this purpose the movable board of said pneumatic has an arm 110 which bears against the rear edge of the thrust bar. The operation of this pneumatic is controlled by a rewind perforation located in each music sheet near its rear end, and coöperating with a corresponding duct of the tracker board, the pneumatic being inflated when the rewind perforation registers with the corresponding tracker duct and deflated when it breaks register therewith, in a manner common to pneumatic actions.

The shipper bar 94 is locked in rewinding position by a vertically-swinging latch 111 pivoted at 112 to the right-hand end piece 1 and engaging a notch 113 in said bar, the latch being constantly urged toward the latter by a spring 114. The withdrawal of this latch for releasing the shipper bar is controlled by the upward or return movement of the transfer arms through the rock shaft 56 carrying said arms, an arm 115 fixed to said shaft and a rod or link 116 connecting said arm 115 with the tail of the latch. This link is pivoted to the arm 115 to move positively therewith but has a limited amount of play or dead movement relative to the tail of the latch, so that the latter is allowed to remain in locking position during the greater part of the upward stroke of the transfer arms but withdrawn during the final portion of said stroke by the engagement of a head or shoulder 117 on said link 116 against the rear side of said latch-tail, as shown in Fig. 8. The moment this latch is withdrawn, the shipper bar 94 and the rocking frame 90 are released, permitting the latter to be swung by its spring 92 in the proper direction to disengage the rewound music roll from the rewind shaft 85. To prevent this rocking frame from swinging far enough to again engage the pinion 84 with the gear wheel 83 of the take-up roll, the shipper bar is provided with a rearwardly-extending pin 118 which engages the outer side of a stop-arm or segment 119 secured to the rock shaft 56 which carries the transfer arms 72. This segment is of the proper length to block said shipper-bar in the elevated position of the transfer arms, as shown in Fig. 8, but to clear and release said pin in the depressed position of said arms, in order to allow the shipper-bar to advance sufficiently to throw the take-up roll into gear with the driving mechanism after said arms have been lowered to transfer the rod 68 of the active music roll to the hooks of the take-up roll, as hereinbefore described. In this last-mentioned position of the shipper bar, which is illustrated in Fig. 9, its pin 118 extends immediately over the nose or straight front edge 120 of said stop-segment and thus blocks the upward move-

ment of the segment and consequently retains the transfer arms in their depressed position until said pin is again withdrawn from the segment by the pneumatic 109, preparatory to rewinding a played roll.

When empty or at rest, the take-up roll is locked in the proper position to receive the rod 68 of a music roll, by a vertically-swinging latch 121 preferably pivoted upon the lower rear tie rod 2 and engaging a notch 122 in the adjacent flange of said roller. This latch is connected with one of the take-up arms by a link 123 in such manner that the latch is held in engagement with the take-up roll in the elevated position of the transfer arms and is swung down out of engagement therewith when said arms are lowered, in order to release the take-up roll by the time it receives the rod of the music roll from said arms.

The wind chest of the automatic musical instrument with which the roll carrier is associated may be flushed by any suitable means, in order to silence the instrument during the rewinding of the music sheets. I preferably employ a flushing device controlled by the roll changer and constructed as follows:

The block 102 contains a flushing port or passage 124 suitably connected with the wind chest and controlled by a flushing valve 125 carried by a lever 126 pivoted to a standard 127 on said block 102, as shown in Fig. 11. The shifting lever 100 carries a laterally-projecting pin 128 which extends over the tail or short arm of the valve-lever 126, so that when the lever is depressed by the thrust-bar 106, its pin 128 depresses the rear arm of the valve-lever, raising the front arm of the latter and opening the valve, thus flushing the wind chest during the rewinding operation. The lever 126 is temporarily locked in this position by a spring catch 129 engaging a pin 126¹ on said lever. The release of this catch is preferably controlled from the shaft of the take-up roll through a horizontal rock shaft 130 arranged below the latter and provided at its outer end with an arm 131 adapted to bear upon the tail of said catch 129 and at its inner end with a similar arm 132 adapted to be depressed by a trip pin 133 carried by the gear wheel 83 on the shaft of the take-up roll.

In practice, the air is exhausted from the wind chest of the musical instrument, as soon as the roll changer is actuated, and unless the music sheet tightly closes the ducts of the tracker-board while its end is being transferred to the take-up roll, the instrument will play numerous discordant notes during this interval. As it is difficult to reliably close the ducts during this transferring operation, the apparatus is preferably so organized that the flushing valve is held open during

that interval and for a short period thereafter. For this purpose the trip-pin 133 of the gear wheel 83 is so arranged that it does not actuate the rock-shaft 130 until a sufficient portion of the sheet has been wound on the take-up roll to cause it to hug the tracker board and close all its ducts preparatory to playing the selections on the sheet in the usual manner. Satisfactory results are obtained by arranging said pin to trip the rock shaft and allow the flushing valve to close, after the take-up roll has made nearly a complete turn.

The operation of the apparatus is as follows: Preparatory to starting the apparatus, the desired music rolls are placed in the carrier. In the normal inactive position of the parts, the take-up roll is out of gear with its driving pinion 84, the clutch member of the rewind shaft 85 is retracted to its inoperative position, and the flushing valve is open, as shown in Fig. 1. The take-up roll is locked in position ready to receive the rod 68 of the music roll to be played and the transfer arms 72 are elevated ready to receive the ends of said rod upon a partial forward rotation of the roll carrier. At the same time the leaf-spring 54 is relaxed, allowing the spiral spring 57 to draw the movable clutch member 85 into engagement with the corresponding clutch-member of the sprocket wheel 48, which latter forms part of the rotating mechanism of the roll carrier, thus throwing this mechanism into gear with the main driving shaft. The locking-latch of the retaining lever 58 is at the same time held out of engagement with said lever by the pin 82, as shown in Fig. 4. The operator now sets the roll carrier by hand to play the desired music roll, and then closes the motor circuit by the deposit of a coin or otherwise. The shaft 83 and the shaft 26 of the roll unwinding and rewinding mechanism are thereby constantly rotated. The roll carrier is first automatically turned forward a step to bring a roll into playing position by the rotation of the sprocket wheel 41 whose pin 40 enters and leaves one of the radial slots of the wheel 38, giving the latter and the carrier a partial turn, the spring-pressed retaining lever yielding and permitting this action because it has not yet been locked by its latch 63. By the continued rotation of said sprocket wheel, its trip pin 79 engages the actuating arm 80 of the rock shaft 56, turning said shaft in the proper direction to lower the transfer arms 72, which now withdraw the rod 68 of the active music roll from the notches of the carrier and deliver it to the hooks of the take-up roll. By this rocking movement of the shaft 56, the locking latch 63 is released and allowed to rise into engagement with the retaining lever of the roll carrier; the locking latch 121 of the take-up

roll is withdrawn; and the leaf-spring 54 is tensioned by the cam 55, so that by the continued rotation of the sprocket wheel 41, the nose of the controlling lever 50 enters the notch of said wheel, allowing the upper end of said lever to swing farther inward and rocking the clutch lever 46 in the proper direction to disengage the clutch members 44, 45 thereby permitting said sprocket wheel to remain at rest, as hereinbefore described. The forward rotation of said rock shaft 56 also causes the withdrawal of its segment 119 from the stop-pin 118 of the shipper bar 94, as shown in Fig. 9, thus releasing the rocking frame 90 and allowing its spring 92 to swing it into proper position to throw the pinion 84 into gear with the take-up roll, as shown in Fig. 9. The take-up roll is now rotated in the proper direction to unwind the music sheet from the active music roll, and after nearly a complete turn of the take-up roll the trip-pin 133 depresses the arm 132 of the rock shaft 130, thereby releasing the locking catch 129 of the flushing valve 125 and allowing the latter to close, placing the wind chest under tension and causing the instrument to play automatically in the customary manner. When the music roll has been nearly unwound, its rewind perforation, hereinbefore referred to, registers with the corresponding duct of the tracker-board, causing the collapse of the shipper pneumatic 109 which now shifts the thrust bar 106 into engagement with the cam 107 which latter thereupon moves the shipper bar 92 through the connections hereinbefore described, in the proper direction to reverse the position of the rocking frame 90, thus throwing the played music roll into gear with the rewind shaft and the take-up roll out of gear with its driving pinion 84. The shipper-bar is locked in this position by the latch 111. The music sheet is now rewound upon said music roll and upon being fully unwound from the take-up roll, its end bar 68 engages the notches 73 of the depressed transfer arms and elevates the latter, the final portion of the upward stroke of these arms being effected by the spring-pressed lever 75 engaging the cam 77 of the rock shaft which carries said arms, as hereinbefore described. During the first part of the upward movement of these arms the latch-controlling link 116 slides idly on the tail of the latch, but during the final portion of said stroke, the shoulder 117 of said link abuts against said tail and swings the latch out of engagement with the shipper-bar 94. The latter being now released, the spring 96 urges the rocking frame 90 toward its former position, but before the frame swings far enough to again throw the pinion 84 into gear with the driving wheel 83 of the take-up roll, the stop pin 118 of the shipper-bar encounters the stop

segment 119 which has in the meantime been moved in front of it by the return movement of the rock shaft 56, thereby locking said rocking frame in its vertical or neutral position, in which both the take-up roll and the rewound music roll are out of gear with the driving mechanism. After leaving the transfer arms, the rod 68 of the rewound music roll reenters the notches 70 of the roll-carrier. 75

By the backward rotation of the rock shaft 56 produced by the upward stroke of the transfer arms, the cam 55 is withdrawn from the leaf-spring 54, removing the tension from the lever 50 whose upper end is now retracted from the notch of the sprocket wheel 41 by the spiral spring 57, thereby withdrawing the slotted link 49 from the upper arm of the clutch lever and allowing the spring 48 of the latter to shift the clutch member 45 carried by said lever into engagement with the corresponding clutch member 44. The actuating mechanism of the roll-carrier is thereby again thrown into gear with the main driving shaft, preparatory to advancing the carrier another step and bringing the next music roll into playing position by the deposit of another coin, whereupon the above described cycle of operations is repeated. 80 85 90 95

The positive locking devices 58 and 63 of the roll-carrier and the sheet-transferring devices which control the same are so constructed and arranged that the carrier is locked in position before the pin 40 of the actuating wheel 41 leaves the active slot of the wheel 38. This prevents the carrier, after having been properly advanced, from being disturbed or moved out of position by persons tampering with the apparatus. 100 105

The spring pressed lever 75 and cam 77 by completing the upward stroke of the transfer arms, serve to raise them far enough to clear the music-roll rods seated in the notches of the roll-carrier. The transfer arms are thus prevented from pushing said rods out of said notches when the roll carrier is rotated, which would otherwise occur. 110

Any suitable coin-controlled device may be employed for automatically starting the apparatus and stopping it after the playing of each music roll. This mechanism forms no part of my present invention and therefore is not illustrated. 115

Various changes or modifications of the apparatus may obviously be made within the scope of the appended claims, and some parts of the mechanism may be used independently of others, and I do not therefore wish to be limited to the particular construction of the apparatus herein shown and described. 120 125

I claim as my invention:

1. The combination of a traveling carrier adapted to carry a plurality of music rolls, 130

5 a take-up roll, means for alternately driving the take-up roll and one of the music rolls, and automatic means for intermittently advancing said carrier to bring different music rolls in operative relation to the take-up roll.

2. The combination of a rotatable carrier adapted to carry a plurality of music rolls, a take-up roll, means for alternately driving the take-up roll and one of the music-rolls, 10 and automatic means for intermittently rotating said carrier.

3. The combination of a rotatable carrier adapted to carry a plurality of music rolls, a take-up roll, means for alternately driving 15 the take-up roll and one of the music-rolls, automatic means for intermittently rotating the roll carrier, and means for locking the carrier in position after each movement thereof.

20 4. The combination of a rotatable carrier adapted to carry a plurality of music-rolls, a take-up roll, means for alternately driving the take-up roll and one of the music-rolls, transfer means for delivering the ends of 25 the music sheets to the take-up roll, means for intermittently rotating the roll-carrier, and locking means for the carrier controlled by said transfer means.

5. The combination of a rotatable carrier 30 adapted to carry a plurality of music rolls, a take-up roll, means for alternately driving the take-up roll and one of the music-rolls, means for intermittently rotating the roll-carrier, locking means for the carrier, and 35 transfer means for delivering the ends of the music sheets to the take-up roll, said transfer means controlling said locking means and operating to release the same on the return stroke of the transfer means.

40 6. The combination of a rotatable carrier adapted to carry a plurality of music rolls, a take-up roll, means for alternately driving the take-up roll and one of the music-rolls, means for holding said driving means out 45 of engagement with the take-up roll and the music-rolls, and transfer means for delivering the ends of the music sheets to the take-up roll, said transfer means controlling said holding means.

50 7. The combination of a rotatable carrier adapted to carry a plurality of music rolls, a take-up roll, means for alternately driving the take-up roll and one of the music-rolls, means for holding said driving means out 55 of engagement with the take-up roll and the music rolls, means for intermittently rotating said carrier, means for locking the carrier, and transfer means for delivering the ends of the music sheets to the take-up roll, 60 said transfer means controlling both said locking means and said holding means.

8. The combination of a rotatable roll-carrier, adapted to carry a plurality of music rolls, a take-up roll, transfer means 65 for delivering the ends of the music sheets

to the take-up roll, driving mechanism, means for intermittently rotating the roll-carrier, and means for throwing said carrier rotating means into and out of gear with said driving mechanism.

9. The combination of a rotatable roll-carrier, adapted to carry a plurality of music rolls, a take-up roll, transfer means for delivering the ends of the music sheets to the take-up roll, driving mechanism, 75 means for intermittently rotating the roll-carrier, and means controlled by said transfer means for throwing said carrier-rotating means into and out of gear with said driving mechanism.

10. The combination of a rotatable roll-carrier, adapted to carry a plurality of music rolls, a take-up roll, transfer means for delivering the ends of the music sheets to the take-up roll, driving mechanism, 85 means for intermittently rotating the roll-carrier, and a clutch under the control of said transfer means connecting said carrier-rotating means with said driving mechanism.

11. The combination of a rotatable music-roll carrier, a radially-slotted wheel mounted on the shaft of said carrier, an actuating wheel having a pin arranged to engage the slots of said wheel successively, a take-up roll, means for transferring the ends of the music-sheets to the take-up roll, driving mechanism, and means controlled by said transfer means for throwing said actuating wheel into and out of engagement with said driving mechanism.

12. The combination of a rotatable music-roll carrier, a take-up roll, transfer means for delivering the ends of the music sheets to the take-up roll, means for intermittently actuating said transfer means, driving mechanism, and means for throwing said actuating means into and out of engagement with said driving mechanism.

13. The combination of a music-roll carrier, a take-up roll, a rock shaft carrying a transfer arm arranged to deliver the ends of the music sheets to the take-up roll, said shaft also having a rock arm, a rotary actuating member having a trip pin arranged to engage said rock-arm, and means for driving said actuating member.

14. The combination of a music-roll carrier, a take-up roll, a rock shaft carrying a transfer arm arranged to deliver the ends of the music sheets to the take-up roll, said shaft also having a rock arm, a rotary actuating member having a trip pin arranged to engage said rock-arm, driving mechanism, and means controlled by said rock shaft for throwing said actuating member into and out of engagement with said driving mechanism.

15. The combination of a music-roll carrier, a take-up roll, a rock shaft carrying a 130

transfer arm arranged to deliver the ends of the music sheets to the take-up roll, actuating means for said shaft, driving mechanism, and means controlled by said rock shaft for throwing said actuating means into and out of engagement with said driving mechanism.

16. The combination of a rotatable music-roll carrier, a radially-slotted wheel mounted on the shaft of said carrier, a take-up roll, a rock shaft carrying a transfer arm arranged to deliver the ends of the music-sheets to the take-up roll, said shaft also having a rock arm, an actuating wheel having a pin arranged to engage the slots of said wheel successively, and a second pin arranged to engage said rock-arm, and means for driving said actuating wheel.

17. The combination of a rotatable music-roll carrier, a radially-slotted wheel mounted on the shaft of said carrier, a take-up roll, a rock shaft carrying a transfer arm arranged to deliver the ends of the music-sheets to the take-up roll, said shaft also having a rock-arm, an actuating wheel having a pin arranged to engage the slots of said wheel successively and a second pin arranged to engage said rock-arm, driving mechanism, and a clutch controlled by the movement of said rock shaft for connecting said actuating wheel with said driving mechanism.

18. The combination of a rotatable music-roll carrier, an actuating wheel for said carrier having a recess, driving mechanism, a clutch for connecting said actuating wheel with said driving mechanism, a controlling lever for said clutch normally bearing against said actuating wheel and adapted to engage the recess thereof to change the position of the lever and the clutch.

19. The combination of a rotatable music-roll carrier, an actuating wheel for said carrier having a recess, driving mechanism, a clutch for connecting said actuating wheel with said driving mechanism, a controlling lever for said clutch normally bearing against said actuating wheel and adapted to engage the recess thereof to change the position of the lever and the clutch, means for pressing said lever against said wheel, and means for withdrawing said lever from said recess when the lever is released from said pressing means.

20. The combination of a rotatable music-roll carrier, an actuating wheel for said carrier having a recess, driving mechanism, a clutch for connecting said actuating wheel with said driving mechanism, a controlling lever for said clutch normally bearing against said actuating wheel and adapted to engage the recess thereof, a spring tending to press said lever against said wheel, means for tensioning and relaxing said spring, and a second spring tending to withdraw said

lever from said recess when the first-named spring is relaxed.

21. The combination of a rotatable music-roll carrier, an actuating wheel for said carrier having a recess, driving mechanism, a clutch for connecting said actuating wheel with said driving mechanism, a controlling lever for said clutch normally bearing against said wheel and adapted to enter the recess thereof, a take-up roll, a rock-shaft carrying a transfer arm arranged to deliver the ends of the music sheets to the take-up roll, said shaft also carrying a member arranged to press said lever against said wheel in the lowered position of the transfer arm and to release the lever in the raised position of said arm, and a spring for withdrawing said lever from said recess when released by said pressure member.

22. The combination of a rotatable music-roll carrier, an actuating wheel for said carrier having a recess, driving mechanism, a clutch for connecting said actuating wheel with said driving mechanism, a controlling lever for said clutch normally bearing against said actuating wheel and adapted to engage the recess thereof, said lever having a spring which when tensioned presses the lever against said wheel, a take-up roll, a rock shaft carrying a transfer arm for delivering the ends of the music sheets to the take-up roll and a cam arranged to tension said lever spring when the transfer arm descends and to recede from said spring when the transfer arm ascends, and a second spring tending to withdraw said lever from said recess.

23. The combination of a rotatable music-roll carrier, an actuating wheel for said carrier having a recess, driving mechanism, a clutch for connecting said actuating wheel with said driving mechanism, a shifting lever for said clutch, a spring for swinging said lever in one direction, a controlling lever normally bearing against said actuating wheel and adapted to engage the recess thereof, a bar attached to said controlling lever and engaging said clutch lever to swing the same in the opposite direction, a second spring acting on said controlling lever to press the same against said actuating wheel when tensioned, a rock shaft carrying a cam bearing against the last-named spring, means for actuating said shaft, and a third spring tending to withdraw said controlling lever from said recess.

24. The combination of a rotatable music-roll carrier, a notched wheel secured to the shaft of the carrier, a lever interlocking with said wheel, and locking means for said lever.

25. The combination of a rotatable music-roll carrier, a wheel secured to the shaft of the carrier and having V-shaped notches, a spring-pressed lever engaging said notches, and locking means for said lever.

26. The combination of a rotatable music-roll carrier, a take-up roll, transfer means for delivering the ends of the music sheets to the take-up roll, and locking means for said carrier controlled by said transfer means. 5
27. The combination of a rotatable music-roll carrier, a locking device for said carrier, a spring tending to move said locking device in one direction, a rock shaft, and a member on said rock shaft engaging said locking device to move the same in the opposite direction. 10
28. The combination of a rotatable music-roll carrier, a retaining lever for the carrier, a locking latch for said lever, a spring tending to hold the latch in engagement with said lever, and a rock shaft carrying a projection arranged to move the latch out of engagement with the lever. 15
29. The combination of a rotatable music-roll carrier, a notched wheel secured to its shaft, a retaining lever engaging said wheel, a locking latch for said lever, a spring tending to hold the latch in locking position, a take-up roll, and a rock shaft carrying a transfer arm for delivering the ends of the music sheets to the take-up roll and a projection arranged to engage said latch for withdrawing the same from said lever. 20
30. The combination of a rotatable music-roll carrier, a take-up roll, means for alternately driving said take-up roll and one of the music-rolls, means for holding the driving mechanism in position to rewind the music sheet on the active music roll, a rock shaft carrying a transfer arm for delivering the ends of the music sheets to the take-up roll, a connection between said rock shaft and said holding means for releasing the latter on the return stroke of the transfer arm, and means for effecting the return stroke of said shaft. 35
31. The combination of a rotatable music-roll carrier, a take-up roll, means for alternately driving said take-up roll and one of the music rolls, means for holding the driving mechanism in position to rewind the music sheet on the active music roll, a rock shaft carrying a transfer arm for delivering the ends of the music sheets to the take-up roll, a connection between said rock shaft and said holding means for releasing the latter on the return stroke of the transfer arm, and spring-pressed means acting on said shaft to effect the final portion of its return stroke. 45
32. The combination of a rotatable music-roll carrier, a take-up roll, means for alternately driving said take-up roll and one of the music rolls, means for holding the driving mechanism in position to rewind the music sheet on the active music-roll, a rock shaft carrying a cam and a transfer arm for delivering the ends of the music sheets to the take-up roll, a connection between said rock 50

- 60
- 65
- shaft and said holding means for releasing the latter on the return stroke of the transfer arm, and a spring-pressed lever bearing against said cam. 70
33. The combination of a rotatable music roll carrier, a take-up roll, mechanism for alternately driving said take-up roll and one of the music rolls, a shipper bar for moving said driving mechanism into position to rewind the music sheet on the active music roll, a locking latch for said shipper bar, a rock shaft carrying a rock arm and a transfer arm for delivering the ends of the music sheets to the take-up roll, and a rod connecting said locking latch with said rock arm. 75
34. The combination of a rotatable music roll carrier, a take-up roll, mechanism for alternately driving said take-up roll and one of the music rolls, a shipper bar moving said driving mechanism into position to rewind the music sheet on the active music roll, a locking latch for said shipper bar, a rock shaft carrying a rock arm and a transfer arm for delivering the ends of the music sheets to the take-up roll, a rod connecting said locking latch with said rock arm and movable independently of said latch during a portion of the return stroke of said rock arm. 80
35. The combination of a rotatable music roll carrier, a take-up roll, mechanism for alternately driving said take-up roll and one of the music rolls, a shipper bar for moving said driving mechanism into position to rewind the music sheet on the active music roll, a locking latch for said shipper bar, a rock shaft carrying a rock arm and a transfer arm for delivering the ends of the music sheets to the take-up roll, a rod connecting said locking latch with said rock arm and movable independently of said latch during the initial portion of the return stroke of said rock shaft, a cam secured to said shaft, and a spring-pressed lever bearing against said cam for effecting the final portion of said return stroke. 85
36. The combination of a rotatable music-roll carrier, a take-up roll, a transfer means for delivering the ends of the music sheets to the take-up roll, and locking means for the take-up roll controlled by said transfer means. 100
37. The combination of a rotatable music roll carrier, a take-up roll, mechanism for alternately driving the take-up roll and one of the music rolls, a shipper bar controlling the position of said driving mechanism, a rock shaft carrying a transfer arm for delivering the ends of the music sheets to the take-up roll, and a stop-member on said rock shaft arranged to limit the movement of the shipper bar in one position of said transfer arm and to clear and release said bar in another position of the transfer arm. 105

- 130

38. The combination of a rotatable music-roll carrier, a take-up roll, mechanism for alternately driving the take-up roll and one of the music rolls, a shipper bar controlling the position of said driving mechanism and having a projection, a rock shaft carrying a transfer arm for delivering the ends of the music sheets to the take-up roll, and a stop segment secured to said rock shaft and constructed to engage said projection in the elevated position of said transfer arm and to clear the same in the depressed position of said arm.

39. The combination of a rotatable music-roll carrier, a take-up roll having a locking notch, a rocking transfer arm for delivering the ends of the music sheets to the take-up roll, a locking latch arranged to engage said notch, and means connecting said latch with said transfer arm.

40. The combination of a music-roll carrier, a take-up roll, a flushing valve, means for transferring the ends of the music sheets to the take-up roll, means for holding said flushing valve open during said transferring operation, and automatic means for closing said valve after said transferring operation.

41. The combination of a music-roll carrier, a take-up roll, a flushing valve, means for transferring the ends of the music sheets to the take-up roll, means for holding said flushing valve open during said transferring operation, and means controlled by the rotation of the take-up roll for closing said valve.

42. The combination of a music-roll carrier, a take-up roll, a flushing valve, a catch for holding said valve open, a rock shaft having a trip arm and an arm arranged to engage and release said catch, and a trip member carried by the shaft of the take-up roll and arranged to engage said trip-arm.

43. The combination of a rotatable music-roll carrier, a take-up roll, mechanism for alternately driving said take-up roll and one of the music rolls, a shipper bar for moving the ends of the music sheets to the take-up roll, locking means for said shipper bar, and means for transferring the ends of the music sheets to the take-up roll, said transferring means controlling said locking means.

44. The combination of a rotatable music-roll carrier, a take-up roll, mechanism for

alternately driving the take-up roll and one of the music rolls, a shipper bar controlling said driving mechanism, a rock shaft carrying a transfer arm for delivering the ends of the music sheets to the take-up roll, and a stop-member on said rock shaft arranged to engage a part of said shipper bar to lock said transfer arm in its depressed position.

45. The combination of a rotatable music-roll carrier, a take-up roll, mechanism for alternately driving the take-up roll and one of the music rolls, a shipper bar controlling said driving mechanism and having a projection, a rock shaft carrying a music-sheet transfer-arm, and a stop-segment secured to said rock shaft and constructed to engage said projection in the elevated position of said transfer-arm and clear the same in the depressed position of said arm, said segment having a part arranged to engage under said projection in the take-up position of said driving mechanism, to lock said transfer-arm in its lowered position.

46. The combination of a traveling music-roll carrier, a radially-slotted wheel mounted on the shaft of said carrier, an actuating wheel having a pin arranged to engage the slots of said wheel successively, means for intermittently driving said actuating wheel, locking means for the roll-carrier, and automatic means arranged to move said locking means into position to lock the carrier before said pin moves out of engagement with said slotted wheel.

47. The combination of a traveling music-roll carrier, a radially-slotted wheel mounted on the shaft of said carrier, an actuating wheel having a pin arranged to engage the slots of said wheel successively, means for intermittently driving said actuating wheel, locking means for the roll-carrier, a take-up roll, and means for transferring the ends of the music-sheets to the take-up roll, said transferring means controlling said locking means to lock the carrier before said pin moves out of engagement with said slotted wheel.

Witness my hand this 17th day of September, 1912.

FRANK L. McCORMICK.

Corrections in Letters Patent No. 1,110,001.

It is hereby certified that in Letters Patent No. 1,110,001, granted September 8, 1914, upon the application of Frank L. McCormick, of North Tonawanda, New York, for an improvement in "Automatic Roll-Changers for Musical Instruments," errors appear in the printed specification requiring correction as follows: Page 4, line 116, after the compound word "shipper-bar" insert the word *pin*; page 5, line 66, for the word "fluishing" read *flushing*; and that the said Letters Patent should be read with these corrections therein that the same may conform to the record of the case in the Patent Office.

Signed and sealed this 13th day of October, A. D., 1914.

[SEAL.]

J. T. NEWTON,

Acting Commissioner of Patents.
